(57) **CLAIM**

The ornamental design for a birdfeeder, as shown.

DESCRIPTION

FIG. 1 is a perspective view of a birdfeeder showing our new design;

FIG. 2 is a front elevational view thereof;

FIG. 3 is a top plan view thereof;

FIG. 4 is a bottom plan view thereof;

FIG. 5 is a side elevational view thereof; and,

FIG. 6 is a rear elevational view thereof.

The broken lines in FIGS. 1-6 are for purposes of illustration only and form no part of the claimed design.
